UNITED STATES PATENT OFFICE.

NILS MATHIAS ROSENDAHL, OF CHICAGO, ILLINOIS, ASSIGNOR TO FREDERICK C. AUSTIN, OF CHICAGO, ILLINOIS.

MATERIAL-HOIST.

1,176,247.

Specification of Letters Patent. Patented Mar. 21, 1916.

Application filed April 29, 1912. Serial No. 693,869.

To all whom it may concern:

Be it known that I, NILS M. ROSENDAHL, a citizen of the United States of America, and resident of Chicago, Cook county, Illinois, have invented a certain new and useful Improvement in Material-Hoists, of which the following is a specification.

My invention relates to material hoists of the kind used in buildings for elevating materials from the ground to the different floors of the building, either while the building is in course of construction, or merely for the purpose of carrying materials to the different floors of a building after the construction thereof has been completed.

Generally stated, the object of my invention is to provide an improved and highly efficient material hoist for use in distributing materials to the different floors or levels 20 of a building or other structure.

Special objects are to provide a material hoist of this kind in which the bucket is side-tracked to discharge its load at any particular floor or level of the structure in connection with which the hoist is employed; to provide an improved construction and arrangement whereby the bucket tilts automatically and of its own accord to operate a switch that controls the said side track; to provide an improved construction and arrangement whereby the switches for the side tracks of the different floors or levels are manually controlled from the ground, or from a point below, whereby any particular switch can be locked in one position to keep the bucket or carrier from running onto a certain side track, and in another position to keep the side track open; to provide an improved construction and arrangement whereby the bucket is held in position for loading, by parallel tracks at the base of the vertical or main track, and is then disengaged from certain of these lower tracks when it changes its course in passing therefrom to the main track; to provide an improved construction and arrangement whereby the weight of the bucket is utilized for automatically opening the switch in the main track to permit the said bucket or carrier to pass onto a side track; and to provide certain details and features of improvement tending to increase the general efficiency and serviceability of a material hoist of this particular character.

To the foregoing and other useful ends,

my invention consists in matters hereinafter set forth and claimed.

In the accompanying drawings—Figure 1 is a front elevation of a material hoist embodying the principles of my invention, 60 showing the upper portion thereof broken away for convenience of illustration. Fig. 2 is a vertical section on line 2—2 of Fig. 1.

As thus illustrated my invention comprises an upright frame or body structure 65 A which provides a shaft in which the bucket B travels up and down. The main track for the bucket consists of a single vertical rail C at each side of the said shaft or well, in which the bucket travels up or 70 down, the said rails being of any suitable known or approved character. In this case, however, each rail is made of channel iron to provide grooves or ways for the rolls or wheels b and b¹ mounted on the sides of the 75 said bucket. At its lower end the track is formed with parallel and inclined portions c and c¹ which permit the bucket to stand at the front of the structure while loading, thus facilitating the use thereof. The rolls 80 or wheels b travel in the track portions c, there being one at each side, and the rolls or wheels b¹ travel in the track or section c¹, the latter being open at its upper end. The rolls b and b¹ are so disposed or located on 85 the sides of the bucket that the latter is heavier at the rear thereof than at its front or outer end. The bucket is provided with another pair of rolls or wheels c² that travel in the track portions c¹ and which are disengaged or released by the upper ends of these track portions when the bucket changes its course in passing onto the main track. At a point above, the track is provided with a side track D which projects laterally from 90 the main track and which is of such character that it tilts the bucket over to discharge the load therefrom.

The switch E consists of movable track sections e pivoted at e¹ and disposed in position to control the said side switch. A horizontal rock shaft F is mounted upon the front of the frame or structure A and provided with bell crank arms f which are connected by rods f¹ with the track sections e of the switch. These arms f are provided with weights f² which tend normally to keep the said switch closed. A locking bolt f³, of any suitable character, and preferably controlled by a spring which moves it into 95 100 105 110

position, engages the said arm f to hold it in either position, whereby the switch is locked in either closed or open position. As shown in Fig. 2 the said switch is locked in closed position by reason of the fact that the bolt f^3 is in engagement with the upper edge of the arm f . When the said shaft is rocked and the arms f are moved to positions shown in dotted lines, the locking bolt f^3 then engages the lower edge of the arm f , thereby locking the switch in open position. A sheave f^4 is mounted upon the frame or structure A, and the said bolt f^3 is provided with an operating cord or chain f^5 which runs over the said sheave and hangs down to a point where it can be grasped and operated by a person standing on the ground. The bucket may be of any suitable or desired construction, and is operated in any suitable manner, an operating line or cable G being ordinarily provided for this purpose. When the bucket starts upward, after being loaded, the rolls or wheels c^2 leave the upper end of the track portions c^1 and the rolls or wheels b and b^1 then travel upward in the rails of the vertical or main track, and if the side switch is closed, the bucket or carrier will pass the side track. If, however, it is desired that the bucket shall discharge its load at the floor or level at which the said side track is located, the operator or attendant will then pull the cord or chain f^5 to unlock the switch, and as soon as the upper rolls or wheels of the bucket encounter the switch, the preponderance of weight at the inner side of the bucket will cause it to tilt over in this direction. This tilting motion of the bucket causes the rolls or wheels b to move the switch into open position, as shown in dotted lines in Fig. 2, and the bucket then moves out upon the side track and proceeds to dump its load, in the manner shown in dotted lines in Fig. 2. The operator or attendant manipulates the cord or chain f^5 for the purpose of locking the switch in open position, and thus the bucket will travel backward upon the side track and be free to return to the main track after it has discharged its load. The main track may have as many side tracks and switches therefor as are found necessary for any particular purpose. The track is made in sections, as shown, the sections being joined together by the bracket plates H, whereby the track can be made higher from time to time as the construction of the building progresses, and in this way the materials can be hoisted and delivered to any particular floor. All of the switches of the different side tracks are controllable from the ground or from a point below, and thus the operator or attendant can control the hoist and cause the material to be discharged at any desired floor or level. The bucket may operate up

and down, discharge its load several times at any particular floor, or it may rise and discharge its load at one floor and then discharge the next load at another floor. Each side track is disposed in such position that it automatically tilts the bucket to dumping position.

I do not limit myself to the exact construction shown and described.

What I claim as my invention is:

1. A material hoist comprising a tilting carrier, a main track therefor, a side track for deflecting the upwardly moving carrier from the said main track, adapted to permit the carrier to pass upward when the point of delivery is higher, and a switch for said side track, automatically operated by tilting motion of said carrier.

2. A material hoist comprising a carrier, a main track therefor, a side track for deflecting the carrier from the said main track, and a switch for said side track, automatically operated by the said carrier, said main track having two parallel portions for keeping the carrier in position while loading, one said portion having an open end and said carrier having wheels engaging said tracks, one or more of said wheels being released by said open end to permit the carrier to change its course in passing from the said portions to another section of the main track, and to permit the carrier to then ascend the main track.

3. A material hoist comprising a carrier, a main track therefor, and a side track for deflecting the carrier from the said main track, a switch for said side track, means whereby said carrier tilts of its own accord to automatically and by its weight shift said switch to side track position while traveling upward, and means for locking said switch in either open or closed position.

4. A material hoist comprising a carrier, a main track therefor, a side track for deflecting the carrier from the said main track, and a switch for said side track, automatically shifted by the weight of said carrier, said main track being disposed upright, and said carrier consisting of a bucket held in dumping position by the side track.

5. A material hoist comprising a carrier, a main track therefor, a side track for deflecting the carrier from the said main track, and a switch for said side track, automatically operated by the said carrier, said main track having two parallel portions for keeping the carrier in position while loading, one of said portions being open at the end thereof, and said carrier having wheels engaging said tracks, one or more of said wheels being released by said open end to permit the carrier to change its course in passing from the said portions of the main track, and to permit said carrier to then ascend the said main track, said main track

being disposed upright, and said carrier consisting of a bucket held in dumping position by the side track, said switch being operated by one or more of said wheels while the carrier is moving upward.

5 6. A material hoist comprising a carrier, a main track therefor, and a side track for deflecting the carrier from the said main track, a switch for said side track, and means whereby said bucket tilts of its own accord to automatically and by its weight operate said switch to side track position, said main track being disposed upright, and said carrier consisting of a bucket held in dumping position and against tilting by the side track.

10 7. A material hoist comprising a carrier, a main track therefor, a side track for deflecting the carrier from the said main track, and a switch for said side track, automatically operated by the said carrier, said main track being disposed upright, and said carrier consisting of a bucket held in dumping position by the side track, whereby the 15 materials are discharged at a certain floor of the building, a similar side track and switch equipment for another floor of the building, and means for controlling said switches from below, whereby the carrier 20 may pass any side track in either direction.

25 8. A material hoist comprising a carrier, a main track therefor, a side track for deflecting the carrier from the said main track, and a switch for said side track, automatically operated by the said carrier, said main track having two parallel portions for keeping the carrier in position while loading, one of said portions being open at the end thereof, and said carrier having wheels released by said open end to permit the carrier to change its course in passing from the said portion of the main track, and to then ascend the main track, said main track being disposed upright, and said carrier consisting 30 of a bucket held in dumping position by the said track whereby the materials are discharged at a certain floor of the building, a similar side track and switch equipment for another floor of the building, and means 35 for controlling said switches from below, whereby the carrier may pass any side track in either direction.

40 9. A material hoist comprising a carrier, a main track therefor, a side track for deflecting the carrier from the said main track, a switch for said side track, and means whereby said bucket tilts of its own accord to automatically operate said switch to side track position, said main track being disposed upright, and said carrier consisting of a bucket held in dumping position by the side track, whereby the materials are discharged at a certain floor of the building, a similar side track and switch 45 equipment for another floor of the building,

and means for controlling said switches from below, whereby the carrier may pass any side track in either direction.

10 10. A material hoist comprising a carrier, a main track therefor, a side track for deflecting the carrier from the said main track, and a switch for said side track, automatically operated by the said carrier, said main track being disposed upright, and said carrier consisting of a bucket held in dumping position by the side track, and a manually controlled lock for the switch.

15 11. A material hoist comprising a carrier, a main track therefor, and a side track for deflecting the carrier from the said main track, a switch for said side track, automatically operated by the said carrier, said main track having two parallel portions for keeping the carrier in position while loading, one of said portions being open at the end thereof, and said carrier having wheels engaging said tracks, one or more of said wheels being released by said open end to permit the carrier to change its course in passing from the said portion of the main track, said main track being disposed upright, and said carrier consisting of a bucket held in dumping position by the side track, and a manually controlled lock for the switch.

20 12. A material hoist comprising a carrier, a main track therefor, a side track for deflecting the carrier from the said main track, a switch for said side track, and means whereby said bucket tilts of its own accord to automatically operate said switch to side track position, said main track being disposed upright, and said carrier consisting of a bucket held in dumping position by the side track, and a manually controlled lock for the switch.

25 13. A hoisting apparatus comprising a hoisting bucket, an upright main track provided with a lateral deflection at the lower end thereof, to carry the bucket bodily sideways into loading position, and means for holding the bucket against tilting while in loading position, said means including an auxiliary track, said bucket having wheels for engaging said main track, one said wheel at each side of the bucket engaging the auxiliary track when the bucket moves into loading position.

30 14. A hoisting apparatus comprising a hoisting bucket, an upright main track provided with a lateral deflection at the lower end thereof, to carry the bucket bodily sideways into loading position, and means for holding the bucket against tilting while in loading position, said means including an auxiliary track communicating with said main track, and said bucket having means for engaging both said tracks, said bucket having a wheel at each side thereof which passes from the main track to the auxiliary

track when the bucket moves into loading position.

15. A hoisting apparatus comprising a hoisting bucket, an upright track provided with a lateral deflection at the lower end thereof, to carry the bucket bodily sidewise into loading position, and means for holding the bucket against tilting while in loading position, said means including an auxiliary track which releases the bucket to permit the latter to ascend said first mentioned track.

16. A material hoist comprising a runway extending upward, a bucket arranged to travel up and down in said runway, a dumping side track for causing the bucket to tilt about a horizontal axis, a switch movable automatically to switching position for taking the upwardly moving bucket onto the side track, and means for controlling the switch at will.

17. A material hoist comprising a runway extending upward, a bucket arranged to travel up and down in said runway, a dumping side track for causing the bucket to tilt about a horizontal axis, a switch for taking the upwardly moving bucket onto the side track, and means for yieldingly holding said switch in closed position, the switch being pivoted to swing with the tilting of the bucket into side track position.

18. A material hoist comprising a runway extending upward, a bucket arranged

to travel up and down in said runway, a dumping side track for causing the bucket 35 to tilt about a horizontal axis, a switch operated by the weight of the load for taking the upwardly moving bucket onto the side track, and a locking device for holding said switch in either open or closed 40 position.

19. A material hoist comprising a runway extending upward, a bucket arranged to travel up and down in said runway, a dumping side track for causing the bucket 45 to tilt about a horizontal axis, a switch operated by the weight of the load for taking the upwardly moving bucket onto the side track, a weight for operating the switch to closed position, and means for locking 50 said weight in position to keep the switch open.

20. A material hoist comprising a runway extending upward, a bucket arranged to travel up and down in said runway, a 55 dumping side track, and a switch for taking the upwardly moving bucket onto the side track, said switch being pivoted at its lower end to tilt with the weight of the bucket to side track position.

Signed by me at Chicago, Illinois, this 60
26th day of April 1912.

NILS MATHIAS ROENDAHL.
